(57) **CLAIM**

The ornamental design for a secondary optic mount for a firearm as shown and described.

DESCRIPTION

FIG. 1 is an elevated rear right side perspective view of a secondary optic mount for a firearm showing Applicant's new design.

FIG. 2 is an elevated front left side perspective view of the optic mount of FIG. 1.

FIG. 3 is a depressed rear left side view of the optic mount of FIG. 1.

FIG. 4 is a depressed front right side view of the optic mount of FIG. 1.

FIG. 5 is a top plan view of the optic mount of FIG. 1.

FIG. 6 is a rear elevational view of the optic mount of FIG. 1.

FIG. 7 is a left side elevational view of the optic mount of FIG. 1.

FIG. 8 is a right side elevational view of the optic mount of FIG. 1.

FIG. 9 is a bottom plan view of the optic mount of FIG. 1.

FIG. 10 a front elevational view of the optic mount of FIG. 1; and,

FIG. 11 is another elevated rear right side perspective view of the optic mount of FIG. 1, showing the optic mount attached to a scope mount that is attached to an upper receiver of a firearm, the scope mount and firearm upper receiver forming no part of the invention.

The dashed lines in the figures depict portions of the optic mount that form no part of the claimed design. The dash-dot-dashed lines in the figures depict environmental structures that form no part of the claimed invention.
